UNITED STATES PATENT OFFICE.

HERMAN A. KROESCHELL, OF CHICAGO, ILLINOIS, ASSIGNOR TO KROESCHELL BROTHERS, OF SAME PLACE.

STEAM-BOILER.

SPECIFICATION forming part of Letters Patent No. 400,462, dated April 2, 1889.

Application filed July 27, 1886. Serial No. 209,191. (No model.)

To all whom it may concern:

Be it known that I, HERMAN A. KROESCHELL, a citizen of the United States of America, residing at Chicago, in the county of Cook and State of Illinois, have invented certain new and useful Improvements in Steam-Boilers, of which the following is a specification, reference being had therein to the accompanying drawings.

10 This invention has for its object to produce a portable boiler that, with compactness of construction, will provide a large heating-surface, and in which the fuel will be utilized with economy.

15 In the accompanying drawings, Figure 1 represents a longitudinal vertical section through the center of the boiler, and Fig. 2 a sectional plan on line $\alpha\alpha$ in Fig. 1.

Corresponding letters in the several figures 20 of the drawings designate like parts.

A denotes the oval or oblong shell of the boiler, into one end of which is located the cylindrical furnace B, with fuel-feeding cylinder C, of smaller diameter, connected with 25 furnace B by flue-ring a. To the downwardly-projecting end of cylinder C is secured the feed-mouth b, as usual for base-burning furnaces. In the bottom of this furnace B is placed the grate c, and below this is 30 provided the ash-pit D. The opening for furnace-door E is formed in the usual manner by securing with riveting between the front walls of the shell and furnace a cast ring, d, so as to form a hermetic rim around 35 such door through the water-space. The bottom flue-sheet, F, is secured between the rear of furnace B and shell A, and the top flue-sheet, G, is secured to the bottom of smoke-chamber shell H. The shell H has on its 40 lower end a flange projecting from the flue-sheet into the water-space, which prevents the foreign substances which cause foaming to rise to the surface of the water, and thus the steam is kept in a purer state than if this 45 deflector were not there; also by the tapering form given to the shell the products of combustion are made to impinge against the wall of the steam-jacket, thus drying the steam before its exit, which shell is also oval or oblong in shape and sufficiently smaller than 50 shell A, to provide a water and steam space

between, and is closed on top by crown-plate I, which has covered openings e for cleaning the flues, and has smoke-pipe nozzle J. The fuel-feeding cylinder C is projected through 55 the upper flue-sheet, G, through the smoke-chamber H, and through crown-plate I, and is provided with a cover, f. The water and steam space between shells A and H is closed by crown-sheet L. Flues M are secured between flue-ring a and upper flue-sheet, G, to form communications between the furnace and upper smoke-chamber, and flues N and O are secured between flue-sheets F and G, to form communications between the upper 65 and lower smoke-chambers, which upper smoke-chamber being divided by a partition-plate, P, the gases from the fuel passing up through flues M will have to take a down course through flues N and up again through 70 flues O before escaping through nozzle J into the chimney.

The opposite parallel sides of shell A are braced together by bars m.

As will be readily seen, a boiler thus constructed can be moved through narrow doors or openings, is complete in itself without any brick-work, and its submerged return-flues not only afford a large heating-surface for generating steam, but utilize the heat from 80 the fuel with the best results.

This boiler may be built with or without the feed-cylinder C.

I am aware that it is not new to locate a fuel-magazine over a fire-box. I am also 85 aware that up and down return vertical flues have been used heretofore, and therefore do not claim broadly such construction; but

What I do claim is—

The combination, in a steam-generator consisting of a water-jacket composed of an inner and outer shell, the latter extending the full height of the boiler and the former terminating on a line nearly with the grate-bars and the upper tube-sheet, of a second inner upper shell secured to the tube-sheet and to the crown-sheet of the boiler, provided at its lower end with an outwardly-deflecting flange and tapering inwardly to form an increased steam-space, said water-jacket being made of two 95 oblong sections secured by angle-irons, a fire box and magazine surrounded by a nest of 100

fire-tubes, a downward set of tubes, and a nest of upward return-tubes, each set of tubes communicating with a smoke-chamber common to two nests of tubes, the upper chamber being arranged to have the hot gases in contact with the steam-chamber and the tubes submerged, substantially as set forth.

In testimony whereof I affix my signature in presence of two witnesses.

HERMAN A. KROESCHELL.
